UNITED STATES PATENT OFFICE

2,489,485

DISHWASHER TUB CONSTRUCTION

Ray W. Franklin, Chicago, Ill.

Application January 25, 1946, Serial No. 643,349

12 Claims. (Cl. 259—107)

1

This invention relates to dish washers and particularly tub constructions therefor.

A difficulty met with in previously existing forms of washers is that deep drawing of metal, which is necessary to form a deep tub of one piece, is an expensive process.

Another difficulty encountered in prior dish washers concerns the forming of channels or conduits in the tub. It is usual and desirable to provide some form of channel for conducting the wash water from the bottom of the washer to or near the top and directing it onto the dishes. Some washers are constructed with separate conduits leading, for example, outside of the tub to the top; others are constructed by stamping troughs in the side wall and enclosing the troughs with covering strips to form enclosed channels.

The former method of forming channels is too costly in materials and time, and the latter requires too expensive a stamping operation.

My invention is designed to overcome all of these difficulties. The first mentioned difficulty, that is, deep drawing, is overcome by forming the tub of my invention of two pieces, a bottom piece which is shallow and can be formed by a simple operation, and a separate piece forming the side wall which can also be formed by a simple operation. The side wall is then fitted to the bottom piece and soldered to it forming a unitary, deep tub.

The second difficulty, which concerns forming the channels or conduits, is overcome by a special construction which eliminates the necessity of stamping troughs in the side wall. The tub is preferably polygonal in shape rather than circular. One advantage of this shape is that the side wall, which is formed of a single piece, can be shaped by a simple operation of breaking the metal to form straight sides angled with respect to each other. The bottom piece is stamped with open troughs therein, which can be accomplished by a simple operation because the bottom piece is shallow. Channel covering strips are then secured over the open sides of the troughs in the bottom piece and are continued upwardly on the side wall forming vertical channels between the covering strips and the side wall.

An advantage of this arrangement is that the channels need not be water tight since they are on the inside of the washer, but the contact between straight strips of metal constitutes a closure sufficient to conduct water to the upper part of the washer. The strips are soldered to the interior of the tub at intervals for securing them in position.

2

Another feature I have included in my invention is the provision of a sediment receiving space into which particles of food from the dishes will fall, thus keeping the washing water substantially clean.

An additional feature of the invention is the provision of baffle means for preventing the sediment thus taken out of circulating water streams from being drawn back into them.

10 A further new feature which I have included is a means for preventing objects, such as pieces of silverware, from falling into the impeller. This comprises a dome shaped cover over the impeller and provided with openings which are ample for thorough circulation of water but which are provided with shields covering the openings from above and open to the side.

With these and other objects in view, my invention consists in the construction, arrangement 20 and combination of the various parts of my device whereby the objects contemplated are attained, as hereinafter more fully set forth, pointed out in the claims, and illustrated in the accompanying drawings, in which:

25 Fig. 1 is a plan view of a wash tub, with parts broken away;

Fig. 2 is a vertical sectional view on an enlarged scale, taken on line 2—2 of Fig. 1;

Fig. 3 is a sectional view taken on line 3—3 of 30 Fig. 2;

Fig. 4 is a sectional view taken on line 4—4 of Fig. 2;

Fig. 4a is an enlarged view of that portion of Fig. 4 encircled in dot-dash lines;

35 Fig. 5 is a sectional view taken on line 5—5 of Fig. 2;

Fig. 6 is a perspective view of the side wall of the tub;

Fig. 7 is a perspective view of the bottom piece 40 of the tub;

Fig. 8 is a perspective view of a channel strip which is used for forming a channel with the bottom piece and wall of the tub;

Fig. 9 is a perspective view of another channel strip which is used in connection with the channel strip shown in Fig. 8; and

45 Fig. 10 is a vertical sectional view of a portion of a modified form of channel strip.

Referring now in detail to the drawings, the tub is shown as generally octagonal in shape, having alternate long and short sides, or similar to a square with the corners cut off. The shell of the tub comprises a bottom piece B into which is fitted a wall W of the same peripheral shape.

55 The bottom piece B is shaped from a flat piece

of sheet metal by stamping, forming four shallow radial open troughs 10 which have inclined walls 12. At the point where the troughs 10 meet is a plane area 14 of the same depth as the troughs 10. This plane area 14 may be termed a center well for the operation of an impeller. Depressed from the central well 14 is a circular indentation 16 provided with a central circular opening. A low flange surrounding the entire bottom piece is formed in the stamping operation and is shown, sections 18 along the long sides of the tub, and sections 20 along the short sides. At their outer ends the channels 10 curve upwardly and continue into the sections 20 of the low flange.

The side wall W comprising the upper part of the tub is formed from a flat piece of sheet metal and broken to generally octagonal shape to conform to the peripheral shape of the bottom piece B and comprises long sides 22 and short sides 24. A flange or bead 26 is formed on the upper margin of the side wall W to strengthen it, and the ends of the whole piece are secured in a seam 28. The side wall W then fits on the bottom piece B inside of the flange around the periphery of the bottom piece to complete the shell of the tub. The two pieces are soldered or otherwise secured together in liquid-tight relation.

Channel strips A are fitted on the inner surface of the tub to form enclosed water channels therein. The lower or short leg 30 of the channel strip A fits over one of the open troughs 10, and the vertical or long leg 32 continues upwardly on the side wall W along the adjacent short side 24 thereof and contacts the adjoining long sides 22. The edges of the cover piece are bent at an angle to the main part as indicated at 34. The portions 34 on the short leg 30 fit against the inclined walls 12 of the trough 10 (see Fig. 5) and the portions 34 on the long leg 32 engage the long sides 22 of the side wall W (see Figs. 3 and 4). The angle portions 34 are soldered as indicated at 35 to secure the channel strip A in place. The channel strip need not form a liquid tight channel with the shell of the tub since they need only to direct the main body of water passing through them. The long leg 32 is provided with an opening 36 approximately midway of its height and another opening 38 near the top.

Channel strip C is of generally U-shape in cross section, and is bent at an angle linearly to conform to the angle of the channel strip A. The channel strip C is placed between the channel strip A and the shell of the tub with its open side toward the channel strip A. When thus in position, the horizontal leg 40 is disposed in the trough 10 between the short leg 30 of the channel strip A and the bottom piece B (see Fig. 5) and the vertical leg 42 is positioned between the long leg 32 of the channel strip A and the short side 24 of the side wall of the tub (see Figs. 3 and 4). The channel strip C is soldered at intervals to secure it in place. The channel strip A forms an enclosed channel 46 extending from the center well 14 outwardly and continuing upwardly along the side wall of the tub; and the channel strip C forms another channel, 48, disposed centrally of the channel 46, but channel 48 terminates midway up the wall of the tub. The upper end of the leg 42 of the channel strip C is curved as indicated at 49 to direct the water from the channel 48 through the opening 36 into the interior of the tub. A closure member 50

closes the top of the channel 46 forcing the water from the channel 46 through opening 38 into the interior of the tub, and a baffle 52 is secured above the opening 38 to direct the water emerging therefrom slightly downwardly.

An impeller 54 provided with a drive shaft 56, a bearing disc 58 and hub 60 is rotatably mounted in the center well 14 with its bearing disc 58 rotating in the circular depression 16. This impeller may be driven by any suitable power means. Immediately above the impeller 54 is a convex cover or dome 62 having a plurality of circumferential openings 64 for the passage of the wash water through the openings 64 being covered by shields 66 for preventing silverware or other objects from falling into the impeller. It will be noted that shields 66 cover the openings 64 from above, but open outwardly. This arrangement effectively prevents objects from falling through the opening 64, while the shields 66 open in the proper direction for facilitating circulation of the wash water. Secured centrally of the dome 62 is a vertically extending shaft housing 68 adapted to support a basket for containing dishes to be washed. Formed on the marginal edge of the dome 62 is a radially extending supporting surface 70 having a generally upwardly or axially extending curved guard flange 72. The bearing surface 70 is supported by and secured to a plate 74 having a central opening 76 therein, the plate 74 resting on the bottom piece B at the upper level of the troughs 10.

Surrounding the guard flange 72 is a horizontally disposed plate 78 having a downturned edge 80 at its outer margin, a circular opening 82 in the center, and a downturned edge 84 around the margin of the opening 82. The opening 82 is greater in diameter than the guard flange 72 to permit the plate 78 to be removed thereover. The plate 78 is spaced from the side walls 22 of the tub, as shown in Fig. 1, but the downturned edge 80 on the outer margin rests on the channel strips A at the corners of the tub as shown in Fig. 2. The plate 78 is formed with a plurality of openings 86 and shields 88 on the underside thereof opening outwardly from the center of the tub. The plate 78 is spaced from the bottom of the tub forming a space 89 therewith for sediment.

On operation of the impeller the wash water is forced outwardly and upwardly through the channels 46 and 48 and emerges from the openings 36 and 38 into the tub, as indicated by the arrows, and is directed to the center onto the dishes. After the water has been thrown on to the periphery of the tub carrying particles of food from the dishes with it, this sediment then filters down through openings 82 and 86, the spaces between the plate 78 and side wall of the tub into the sediment trap 89. The guard flange 72 prevents any substantial amount of water from the space 89 to be drawn out and thus the sediment is trapped in the space 89. By this means substantially clean water is used in the washing process and obviates the necessity for frequent changing of the water.

In the modified form shown in Fig. 10, the channel 46 is provided with a horizontal extension 90 extending inwardly from the outer edge of the tub a short distance. The lower surface 92 thereof is formed integral with the main body of the channel strip A. The upper edge of the short side 24 of the side wall of the tub is bent inwardly to direct the water from

the channel in that direction and terminates at 94. The extension 92 is provided with upturned sides 96 which extend the depth of the channel forming the sides of the channel along this stretch. A closure member 98 is secured along the top of the horizontal channel 90 and is formed with downturned side portions 100 which fit over the upturned sides 96. In this modification the opening 38 is of course eliminated. The inner end of the channel 90 is provided with a down-turned baffle 102 to direct the water onto the dishes. By this modification more water is directed on the dishes from the top instead of from the sides thereby reaching areas not ordinarily reached.

The tub which I have illustrated and described is octagonal. This is not necessarily the only shape that is feasible, and it may be formed with a greater or lesser number of sides; and it may not even be polygonal, but circular. The channel covering strips can be of other shapes than that shown to cooperate with other shapes of tubs.

Although I have herein shown and described a preferred embodiment of my invention, manifestly it is susceptible of modification and rearrangement of parts without departing from the spirit and scope thereof. I do not, therefore, wish to be understood as limiting this invention to the precise form herein disclosed, except as I may be so limited by the appended claims.

I claim as follows:

1. A tub construction having a bottom, a side wall, and channel means secured to the interior of the tub forming channels in the bottom and continuing upwardly on the side wall, each channel means consisting of two channel strips, one surrounding and enclosing the other thereby forming two channels, the channel strips of each channel means terminating at different points, vertically, on the side wall, and there being an opening in the enclosing channel strip at the upper extremity of each channel and opening into the tub.

2. A tub having a polygonally shaped periphery, the sides of the tub being alternately long and short, channel means disposed vertically adjacent each short side on the interior of the tub, each channel means consisting of two channel strips one surrounding and enclosing the other, each enclosing channel strip being in contact with and secured to the two long sides adjacent their intermediate short side, thereby forming two vertically extending channels between each enclosing channel strip and its respective short side, the channel strips of each channel means terminating at different points, vertically, on the side wall, each enclosing channel strip having an opening therein at the upper extremity of each channel formed thereby communicating with the respective channel and opening into the tub.

3. A tub having a center well formed in its bottom for the reception and operation of an impeller, there being radially extending open troughs formed in the bottom of substantially the same depth as the center well and extending therefrom to the periphery of the tub, and channel strips secured to the lateral edges of the troughs for closing the same, said channel strips extending upwardly along the side wall of the tub and being secured thereto, said channel strips forming enclosed vertical extensions of the channels formed in the bottom.

4. In a tub construction having a center well

formed in the bottom thereof for the reception and operation of an impeller, a plate having a central opening therein secured in the tub and spaced from the bottom thereof, said plate having openings therein for the passage of water and solid particles therethrough, and baffle means for preventing the flow of water from the space between said plate and the bottom of the tub into the impeller well.

10 5. A tub construction having a center well formed in the bottom thereof for the reception and operation of an impeller, a plate having a central opening therein secured in the tube and spaced from the bottom thereof, said plate having openings therein for the passage of water and solid particles therethrough, and vertically extending baffle means in the central opening in said plate and surrounding the impeller well for preventing the flow of water from the space between said plate and the bottom of the tub into the impeller well.

15 6. A tub construction having a center well formed in the bottom thereof for the reception and operation of an impeller, there being enclosed channels formed in the bottom of the tub extending radially from the impeller well and continuing upwardly on the side wall of the tub, said channels having openings therein in the upper part of the tub and directed inwardly, a horizontally disposed plate having a central opening therein secured in the tub and spaced from the bottom thereof, said plate having openings therein for the passage of water and solid particles therethrough, and baffle means for preventing the flow of water in the space between the plate and the bottom of the tub from flowing into the impeller well.

20 7. A tub construction, comprising, a center well formed in the bottom thereof, enclosed 40 channels of substantially the same depth as the center well formed in the bottom of the tub communicating with the center well and extending outwardly therefrom, and vertically extending baffle means surrounding the center well and the 45 entrances into said channels for preventing the flow of water in the outer portion of the bottom of the tub from flowing into the center well.

8. A tub having radially extending open troughs formed in its bottom, said troughs having inclined side walls, and channel strips for enclosing said troughs, each channel strip having a horizontal leg and a vertical leg, the lateral edges of the horizontal leg of each channel strip being in contact with and secured to the inclined 55 walls of the respective trough, and the lateral edges of the vertical leg of each channel strip being bent and in contact with and secured to the side wall, the upper end of the vertical leg having an opening therein.

60 9. In a tub construction, a piece having a bottom element and an upwardly extending flange around the periphery of the bottom element, said bottom element having open troughs stamped in the upper surface thereof, said troughs each having one end terminating adjacent said flange, a side wall formed of a single flat piece shaped to conform to the periphery of said bottom piece, the piece forming said side wall having its peripheral meeting edges secured together to form 65 a continuous peripheral element and being secured to said flange to form a unitary tub, and channel strips secured to the interior of the tub enclosing said open troughs and forming channels with the side wall, said channels being in 70 continuation of said troughs.

10. A tub construction having a center well formed in the bottom thereof for the reception and operation of an impeller, a plate having a central opening therein secured in the tub and spaced from the bottom thereof, said central opening being disposed over said center well, said plate having openings therein for the passage of water and solid particles therethrough, an annular plate of lesser dimension than said central opening having its outer marginal edge secured to the bottom of the tub and covering the outer portion of the impeller well, and vertically extending baffle means secured to the outer marginal edge of the annular plate and extending upwardly through the central opening in the first plate for preventing the flow of water from the space between the first plate and the bottom of the tub into the impeller well.

11. Means for forming channels in a tub having a bottom, and a side wall disposed at an angle to the bottom, comprising in combination, a first channel strip of U-shape cross section and formed as an angle in a linear direction thereby forming legs, the angle between said legs conforming to the angle between the bottom and side wall of the tub, and a second channel strip formed as an angle in a linear direction thereby forming legs, the angle between said legs conforming to the angle between the bottom and side wall of the tub, said first channel strip adapted to be fitted to the tub with its open side facing away from the surface of the tub, said second channel strip adapted to be fitted over and close the open side of said first channel strip thereby forming a closed channel in said first channel strip, said second channel strip being wider than said first channel strip and having its lateral edges downturned and adapted to engage the tub thereby forming a closed channel between said second channel strip and the tub, one leg of the second channel strip being longer than the correspond-

ing leg of the first channel strip and having an opening at the extremity thereof and an opening at the extremity of the first channel strip.

12. Means for forming closed channels in an open trough having a bottom surface and side surfaces, comprising in combination, a first channel strip of U-shape cross section, of less width than the trough adapted to be positioned in the trough with its open side directed upwardly, and a second channel strip adapted to fit over and close the open side of the first channel strip and form a closed channel therewith, the second channel strip being wider than the first channel strip, and the lateral edges of the second channel strip adapted to be secured to the side surfaces of the trough when in position closing the first channel strip, thereby forming a closed channel between the second channel strip and the trough, said channel strips being of different lengths for forming different terminal ends of the respective channels, said second channel strip having an opening at its terminal end and an opening at the terminal end of said first channel strip.
